CLAIM

The ornamental design for a device for carrying a ladder, as shown and described.

DESCRIPTION

FIG. 1 is a front perspective view illustrating a device for carrying a ladder of my new design.

FIG. 2 is a front elevational view of the device for carrying a ladder.

FIG. 3 is a rear elevational view of the device for carrying a ladder.

FIG. 4 is a right side elevational view of the device for carrying a ladder.

FIG. 5 is a left side elevational view of the device for carrying a ladder.

FIG. 6 is a top view of the device for carrying a ladder; and,

FIG. 7 is a bottom view of the device for carrying a ladder.

1 Claim, 5 Drawing Sheets
